United States Patent Office.

TIMOTHY C. BRIDE, OF QUINCY, ILLINOIS.

Letters Patent No. 99,396, dated February 1, 1870.

IMPROVEMENT IN HYDRANTS.

The Schedule referred to in these Letters Patent and making part of the same.

To all whom it may concern:

Be it known that I, TIMOTHY C. BRIDE, of Quincy, in the county of Adams, and State of Illinois, have invented a new and valuable Improvement in Self-Acting Hydrants; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of a vertical central section of my invention.

My invention relates to hydrants, and consists, mainly, in the construction and novel arrangement of devices, whereby a hydrant is made self-acting, and the freezing or wasting of the water obviated.

The letter A, of the drawings, designates the outer casing, of wood or other suitable material.

B represents a cylinder, within which works the plunger C, attached to the lower end of the rod e, whose upper end is pivoted to the lever d.

The plunger is formed of two metal plates, confining between them a leather disk or cup, c', of larger diameter than the plates, and fitting closely the bore of the cylinder B, thereby preventing waste of water.

The lower part of cylinder B is contracted, forming a smaller cylinder, D, into which the water is admitted by the pipe e.

Flanges are cast on the bottom of this cylinder, whereby it is fastened to the floor of the outer casing A, by screws x x.

Screwed into the neck of the cylinder D is a brass box, F. Its cover c' is screwed on.

The valve-stem b' passes down through an opening in the centre of the cover c'.

g is a coiled spring attached to the valve-stem b', and serving to keep the valve b firmly pressed against its seat n, in the bottom of the box F.

Fastened to the lower plate of the plunger C is a coiled spring, m, which serves to raise the plunger, when pressure is removed from the handle d of the hydrant, thus allowing the coiled spring g to raise the valve b, and force it against its seat, thereby cutting off the flow of water.

Water is conducted by the pipe e into the lower cylinder D. Pressure being applied to the handle d of the hydrant, the plunger C is depressed, and the valve b opened. The water now flows from the cylinder D into the box F, whence it flows through the four openings h h into the cylinder B, and thence through the exit-pipe k.

What I claim as my invention, and desire to secure by Letters Patent, is—

The automatic hydrant herein described, having cylinder B, plunger C, with coiled spring m, cylinder D, and box F, with valve b, and spring g.

In testimony that I claim the above, I have hereunto subscribed my name, in the presence of two witnesses.

Witnesses:

TIMOTHY C. BRIDE.
